UNITED STATES PATENT OFFICE

GLENVILLE A. COLLINS, OF LOS ANGELES, CALIFORNIA, ASSIGNOR TO COLLINS WESTERN CORPORATION, OF LOS ANGELES, CALIFORNIA, A CORPORATION OF CALIFORNIA

FURNACE ECONOMIZER, AUXILIARY BOILER, AND WATER SCREEN COMBINED

Application filed July 2, 1926. Serial No. 120,107.

My invention relates to improvements in auxiliary boilers, water screens and furnace economizers.

The general object of my invention is to provide an improved auxiliary boiler wherein the water drums are located outside the boiler walls.

Another object of my invention is to provide a water screen and wall section wherein parts may be readily removed to make any repairs that may be necessary without putting the boiler out of service for an undue length of time.

Other objects of my invention will be apparent from the following description taken in connection with the accompanying drawings, wherein:

Fig. 1 is a vertical cross section through a boiler showing several units of my auxiliary boiler and economizer applied thereto;

Fig. 2 is an enlarged fragmentary section of the combustion chamber of the boiler showing more clearly the details of my invention;

Fig. 3 is a section taken on line 3—3, Fig. 2 showing the method of constructing the combustion chamber walls, and also showing one of the wall sections removed;

Fig. 4 is a cross section showing one of the combustion chamber walls;

Fig. 5 is a sectional view of the combustion chamber looking toward the inner face of the front wall and showing the manner in which the water heating tubes of the water screen may be arranged on either side of a stoking port, and

Fig. 6 is a diagrammatic plan of a boiler with auxiliary boilers showing the various manners in which the steam developed in the auxiliary boilers may be utilized.

Referring to the drawing by reference characters, I have shown a water tube boiler at 10 which comprises a mud drum 11, a water drum 12 and a steam drum 13 with a water leg 14 therebeneath together with three sets of water circulating tubes 15, 16 and 17.

Below the set of tubes 15 I show the combustion chamber 18 whose walls it is desirable to keep cool so that a greater amount of heat may be generated therein without over-

heating and without impairing or destroying them.

Several attempts which involved the use of side walls of tubes or pipes have been made with varying success but all have been objectionable as being closely combined with the boiler parts or on account of limited circulation, limited accessibility and on account of requiring the complete shut down of a boiler for any replacement or repairs.

I will now describe the construction of my device as shown in the accompanying drawings wherein I show top and bottom drums spaced apart. These drums include a water drum 20 and a steam drum 21 connected together by the wall cooling tubes 22 of a water screen and by circulation tubes 23 to provide a complete cycle of circulation. The water drum 20 is connected to a source of water supply by means of a pipe 24. I also provide a blow off valve 25 which is suitably connected to the drum and at one end of the drum 20 I show a manhole 26.

The steam drum 21 is shown as provided on its upper side with a steam pipe 50, a safety valve 27 and a manhole 28 in one end.

The wall cooling tubes 22 extend from out of the side of the water drum 20 through the combustion chamber wall 30 up the inner face of the wall for a distance and out through the wall and into the side of the steam drum 21. Along the inner face of the wall 30 the tubes 22 are spaced approximately one tube apart and preferably with the greater portion of their circumferential surface exposed. The remainder of the tubes 22 are embedded in the walls of the combustion chamber.

I have shown the main boiler as provided with four auxiliary boilers, but it will be understood that the number of auxiliary boilers may be varied without departing from the features of my invention.

The water in each auxiliary boiler will circulate upward in the tubes forming part of the furnace side wall and form steam which will be disengaged in the top drum 21 of the auxiliary boiler which is of substantial size so that dry steam can be drawn off the nozzle if desired. The circulation in the outside tubes will be downward to the mud drum 20.

to thereby provide a ring flow circuit which will avoid any danger of burning tubes that form the furnace side wall.

My construction will provide rapid circulation and steaming as in a main boiler and if desired with my invention I am enabled to provide an auxiliary boiler forming a portion of the side wall of a furnace which is so mounted on rollers or wheels that it can be removed bodily or swung free of the furnace for repairs to itself or access to the furnace in which case the disconnecting of the connections to the auxiliary boiler is all that is required before removing it bodily from the furnace. Such a construction is shown in Fig. 1 at the left where I have shown the lower drum 20 supported in a cradle 31 while the upper drum is supported by pivotal engagement with an arm 32 which is pivoted to the boiler fitting at 33. Beneath the stack 34 at the right in Fig. 1 the upper drum is arranged in a stirrup 35 which is supported by a cross member 36 which is supported in turn by standards 37 arranged on base members 38. The lower drum 20 is supported on the base members and is held in place by a yoke 39. The base members 38 have wheels 40 thereon which may run on tracks 41.

Mounted upon certain of the standards 37 I show a backing plate 42 which has suitable insulating material 43 arranged thereover. Upon this insulating material 43, I arrange refractory material 44 which is preferably in the nature of vertically arranged blocks which are recessed at 45 to receive the pipes 22. The blocks 44 are recessed to receive vertical locking bars 46 and the construction is such that after the pipe connections, to be presently described, have been removed the entire auxiliary boiler can be rolled away from its position for repairs. The refractory material 48' above and below the blocks 44 need not be disturbed when the auxiliary boiler is removed.

In Fig. 4 I have shown a specific arrangement wherein the wall is composed of a plurality of units each unit including the backing plate 42 and refractory block members 44. These refractory members are recessed as explained to fit upon the elongated T headed members 46 which are shown as mounted upon the plate 42. Each plate 42 preferably includes a pair of the T members 46 and two groups of superimposed blocks 44.

Each of the plates 42 is provided with an eye member 47 which may be engaged by lifting device 48 (see Fig. 1) mounted on a trolley 49. The plates are also provided with angle members 47' by which the plates may be connected together.

From the foregoing description it will be apparent that a section of the blocks 44 and their associated parts can be lifted free of the tubes so that quick access may be had to one or more tubes for the purpose of renew-

ing the tubes from the outside or inside of the furnace without causing undue delay.

In addition to using my auxiliary boilers on the two sides and front and rear of a boiler or any portion of the sides, it can be used as a closed feedwater heater in which the water level is maintained in circuit with the boiler feed lines to provide what might be termed a furnace economizer. It is also possible in a boiler employing several of these auxiliary boilers, to use a portion of them as feed water heaters and a portion as auxiliary boilers. When used as auxiliary boilers, it is possible to operate at any pressure desired and independent of the pressure maintained on the main boiler.

The usefulness of this idea might be illustrated as follows: Suppose the main boiler is operating at 400 pound working pressure delivering its steam to a turbine and that boiler auxiliaries such as pumps, etc., are taking their steam from different stages bled from the turbine, say 150 pound pressure. A boiler equipped with my auxiliary boilers would use one or more of the auxiliary units at 150 pounds pressure for operating the auxiliaries and other units could be used as feed water heaters or economizers. Also it would be possible to use steam from the auxiliary boilers at varying pressure for process work instead of bleeding turbines or using exhaust steam or reducing valves taking steam from the main boiler.

When it is desirous to use my invention as an auxiliary boiler for running a pump, a small engine, etc., water is fed to the lower drum 20 by a water supply pipe 24. The circulation is through the tubes 22 to the drum 21 thence down the pipe 23 to the drum 20. The steam is disengaged in a drum 21 and passes through a pipe 50. This pipe 50 has a valve 51 thereon which controls communication to the pipe 52 which is adapted to operate an auxiliary such as an engine 53. When it is desired to use the steam generated by the auxiliary boiler with the steam from the main boiler, the valve 51 and also another valve 54 (to be presently described) are closed and a valve 55 is opened to allow the pipe 50 to communicate with the pipe 56 which is in communication with the main pipe 57 from the main boiler.

If it is desired to use my invention as a feedwater heater for the main boiler supply the valve 63 of the main boiler water supply pipe line 64 is closed as are also valves 51 and 55 and the valve 54 is then opened. This allows the water to flow into the drum 20 from the supply pipe 24 through the tubes 22 wherein it is heated, and into the drum 21 thence through the pipe 65 and through pipe 66 into the main boiler.

The auxiliary boiler is to be built of rolled shells or forged steel headers into which would be expanded standard boiler tubes of

suitable size and curvature. The drums would have manholes or handholes for access in cleaning and would have proper blow down connections.

5 Having thus described my invention, I claim:

1. In a device of the class described, a fire chamber including a side wall, a boiler including water circulating tubes passing through independent apertures in said wall, said boiler being movably mounted whereby it may be bodily moved from the fire chamber.

2. In combination, a fire chamber defined in part by a side wall, a boiler including tubes passing through said wall and exposed throughout a substantial portion of their length to the interior of said fire chamber, drums in which said tubes are engaged and means exterior to said fire chamber connecting said drums, said tubes and wall being so related as to enable the withdrawal of said tubes from the fire chamber, a frame upon which said boiler is mounted and means to transportably support said frame, said means including rollers and a track on which said rollers move.

3. In combination, a fire chamber including a side wall, a boiler including spaced drums and tubes connecting said drums, said tubes passing through said wall and exposed throughout a substantial portion of their length to the interior of said fire chamber, a frame, said boiler and a portion of said wall being supported on said frame, and means to transportably support said frame.

4. In combination, a fire chamber defined in part by a side wall, a boiler including a bank of tubes, each tube passing through said wall at spaced points and exposed throughout a substantial portion of its length to the interior of said fire chamber, an upper drum to which the upper end of said tubes are connected, a lower drum to which the lower end of said tubes are connected, said drums being arranged without said fire chamber, and means including spaced tubes arranged exterior to said fire chamber connecting said drums, said bank of tubes and wall being so related as to enable the withdrawal of the tubes of said bank from the fire chamber and means to support said drums in spaced relation.

In testimony whereof, I hereunto affix my signature.

55 GLENVILLE A. COLLINS.
